CEDRIC CHIVERS, OF BATH, ENGLAND.

BINDING FOR BOOKS.

SPECIFICATION forming part of Letters Patent No. 760,308, dated May 17, 1904.

Application filed March 4, 1904. Serial No. 196,541. (No model.)

To all whom it may concern:

Be it known that I, CEDRIC CHIVERS, a subject of the King of Great Britain, residing at Bath, England, have invented a certain new and useful Improvement in Connection with Bindings for Books, of which the following is a specification.

The invention consists in the combination, with a tight-back form of binding, of a plan of stitching the sections together and attaching the book to its covers so that the tapes or strings which are ordinarily used for that purpose may be dispensed with and a more flexible and consequently stronger binding be produced.

Books have hitherto been sewed upon strings, strips of vellum, or tapes with two objects—one of holding the sheets together, but chiefly for the purpose of attaching the book to the boards which form the covers. With the poorer qualities of paper in modern books it is found that these tapes or strings when permeated with the glue, which is poured into the back of the book after it is sewed, have two disadvantages. In the first place, they offer a resistance to the supple opening of the back when the book is bound, and in the case of vellum strips or tapes they have another disadvantage in that they cover a portion of the back and prevent the glue from flowing freely between the sections. Provided a sufficiently-strong attachment of the board to the book can be made without the use of these strings or tapes the book may be dealt with in a much more efficacious fashion and still more strongly by sewing it in the manner hereinafter described.

In carrying the invention into effect the sections of which the book is made up are stitched together with the usual catch or kettle stitching at or near the ends, and in addition each section is stitched to the next in order by threads, which start from the kettle-stitch, along the inside of the section for about an inch, out through the back over to the next section and inside it for a short distance, then outside and over to the first section again and inside for a similar distance, out and over to the next section again, and so

on until the lower kettle-stitching is reached, each section being similarly attached to its neighbor until the whole book is formed. No tapes or strings, however, are used, so that the whole of the book is subject to the gluing operation and each section is united to its fellow, not only at each kettle-stitch, but at every stitch along its course.

To attach the section to the cover securely in the absence of tapes or strings, the inside first and last two sections of each book are lined with fine jaconette in order to strengthen them, and with the above arrangement of sewing end papers or sections are added on each side so made as to form an additional linen-lined section to each end of the book. These are attached to the book by sewing in the same way as the sections which form the book, so that every stitch in and out of a given section or end paper ties it to its previous and following sheet. Near the top and bottom of the back of the book a piece of tape or strip of jaconette may, if the book is a heavy one, be sewed, and with larger books one or more additional pieces toward the middle of the back. The stitches holding these are made through the linen-lined end sections and end papers only. The ends of these strips are inserted, together with the outside linen flap of the end paper, into the boards and form one of the means of attaching the boards to the book.

The method of book-sewing above described is stronger than sewing as it is ordinarily done for the following reasons: Each stitch ties the section to its fellows. There are fewer holes made by the needle, so that each leaf is stronger in the back, because it has fewer perforations. The two tapes or strips of jaconette are so arranged as to be near the top and bottom of the book, and in this way they make a firmer attachment of the boards to the book than heretofore. After the book is rounded and backed the loose or other backing is now attached by gluing it down to the back of the sections in the usual manner. As an alternative, however, to the usual tight back, which is unsuitable for many kinds of book, I prefer to employ a false back made up of a leather base-piece attached to the back of the

book, to which is previously sewed or suitably attached down and a little way from each edge a stiffening-piece composed of layers of brown paper, card, millboard, or the like, each 5 tapered at its edge and sewed to some pliant strengthening fabric—such as book-linen, canvas, or the like—so that a pocket or space, as with an ordinary loose back, is left between the leather base-piece and the stiffener. The 10 point here to be observed is that the fold of the loose back does not come close to the edge of the back of the book, as does the pared leather itself and as does the ordinary loose back, but it starts to open some one-eighth 15 or one-sixth of an inch inside of the groove. This allows the leather cover of the back to be firmly attached to the groove and to the back of the book before it is thrown off to form the loose back, which has several ad- 20 vantages over the ordinary tight leather back. To the outer face of this backing is finally attached the leather back proper. By means of this plan all the advantages of the open-back form are combined with the advantages 25 of a tight back, and thus a much stronger and more flexible binding results. By the use of this combination of sewing and leather backing a very strong binding is produced, which, however, is so flexible as greatly to 30 enhance the life of the book.

Referring to the accompanying drawing, which is a view of the back of a book having parts of a leather half or false back removed to show the stitching and mode of attachment 35 of the end sections to the covers, *a* represents the sections of which the book is composed, and *b* represents the two end sections by means of which the book is more securely attached to its covers, and which sections *b* are stitched 40 at top and bottom by the usual catch or kettle stitches *d* to the sections *a* and are also attached thereto at more or less frequent intervals between by threads *e*, which attach each section of the book to its neighboring section.

45 Each end section *b* may consist of a number of fly-leaves or a number of the usual leaves sewed together and bound by a strip of some pliant material—such as jaconette, book-linen, or the like—the inner or shorter flap *c* of 50 which is glued to the first sheet of the section *b*, while the outer and longer flap *c'* is left loose for attachment to the covers of the book, as will be hereinafter further described.

The tight back which I prefer to employ, 55 as stated, comprises a false back made up of a leather base-piece *f*, which is glued all over its under side to the back of the sections *a* and *b* and having its outer longitudinal edges pared or skived to prevent the 60 formation of ridges when fastened down. To the leather base-piece *f* is attached by sewing down each edge a stiffening-piece made up of layers of brown paper or the like, *g*, between covering-pieces *h* and *i*, the overlapping edges

of which are sewed together and to the base-piece *f*, so that a pocket or space is left between the latter and the stiffening-piece and forms a false open back. The leather half-back proper, *j*, is glued to the covering *i* of the stiffening-piece and the overlapping edges 65 thereof to the covers in the well-understood manner. The covers are attached to the book by the flaps *c'* of the end sections *b*, which are fastened by gluing or the like means between the boards *k* and *m* of which each cover 70 is made up. By such a construction of binding the book is more firmly held between its covers, since it is attached thereto not only by means of the end sections *b*, which are in 75 turn attached, as described, to the sections *a*, comprising the book, but also through the medium of the half-back proper and the false back. The tapes, which have hitherto been a necessary feature of the tight-back form of 80 binding, as they formed the chief means of attachment of the book to its covers, are therefore dispensed with and a source of stiffness and opposition to the easy-opening back of 85 the book, as already described, removed. For the purpose, however, of strengthening the at- 90 tachment of the boards to a heavy or large book at the upper and lower ends, where the pull on the book is principally felt, I prefer to employ a loose tape *n*, attached by stitching to the two end sections only, *b*, the loose ends 95 *n'* of such tapes being inserted between the boards of the cover with the flap *c'*, so that the part which stretches across the back will assist the action of the tight back *f*, underneath which such tapes are glued when the 100 back *f* is stuck down.

What I claim is—

1. A binding for books comprising sections stitched together by threads passing backward and forward between each of every two adjacent sections, end sections secured thereto, a pliant fabric secured to the back edges of the end sections and exposing-flaps, covers comprising boards between which such flaps are secured, and a tight back of leather cemented 105 to the sections.

2. A binding for books comprising sections stitched together by threads passing backward and forward between each of every two adjacent sections, end sections secured thereto, a pliant fabric secured to the back edges of the end sections and exposing-flaps, covers comprising boards between which such flaps are secured, and a false open back comprising a leather base-piece cemented to the sections, a 115 stiffening-piece covered with pliant material and attached by stitches to the said leather base-piece to form a pocket, and a back cemented to said stiffener and to the covers.

3. A binding for books comprising sections 120 stitched together by threads passing backward and forward between each of every two adjacent sections, end sections secured thereto, a

pliant fabric secured to the back edges of the end sections and exposing-flaps, tapes attached by stitching to the two end sections and having loose ends, covers comprising boards between which said flaps and loose ends of said tapes are secured, and a tight back cemented to the sections and to the covers.

In testimony whereof I have hereunto set my hand in the presence of two subscribing witnesses.

CEDRIC CHIVERS.
